(21) Appl. No.: **29/114,489**

(57) CLAIM

(22) Filed: **Nov. 23, 1999**

The ornamental design for a compressed fabric article package having a simulated doughnut shape, as shown.

(51) LOC (7) Cl. **09-03**

DESCRIPTION

(52) U.S. Cl. **D9/329**

FIG. 1 is a perspective view of a compressed fabric article package having a simulated doughnut shape of the present invention, showing my new design;

(58) Field of Search **D1/120; D9/307, D9/329; D11/131; 206/457; 229/116.1-116.5; 428/7, 11, 542.2, 542.8**

FIG. 2 is a side elevation view thereof; and,
FIG. 3 is a rear view thereof.
